UNITED STATES PATENT OFFICE.

SAMUEL T. THORSON, OF BOSTON, MASSACHUSETTS.

CHECK-PROTECTOR.

1,209,076.

Specification of Letters Patent. Patented Dec. 19, 1916.

Application filed February 9, 1916. Serial No. 77,796.

To all whom it may concern:

Be it known that I, SAMUEL T. THORSON, a citizen of the United States of America, and a resident of Boston, in the county of 5 Suffolk and State of Massachusetts, have invented certain new and useful Improvements in Check-Protectors, of which the following is a specification.

This invention relates to check perforators, and has for its object the production in a machine having a plurality of alined perforating devices of means for moving the check a predetermined distance at the completion of each operation of either of the 15 perforating devices.

The present invention is an improvement upon the device shown and described in Letters Patent, No. 1,153,832, issued to me Sept. 14, 1915.

20 The invention consists of a movable carriage adapted to travel in a path parallel to the alined perforating devices and having mounted thereon a pivoted member adapted to actuate a selected perforating device.

25 It further consists in mechanism associated with said actuating member for feeding the check automatically a predetermined distance during the return of said actuating lever to its normal position at the completion of each perforating operation.

30 It further consists in providing the traveling carriage with manually controlled means for feeding the check. The invention further consists in certain novel features of construction and arrangement of parts which will be fully understood by reference to the description of the drawings and to the claims hereinafter given.

35 Of the drawings, Figure 1 represents a plan of a machine embodying the principles of the present invention. Fig. 2 represents a front elevation of the same. Fig. 3 represents a vertical section of the same on line 3—3 on Fig. 1. Fig. 4 represents a rear elevation of the traveling carriage and actuating device. Fig. 5 represents a side elevation of the same. Fig. 6 represents an inverted plan of the end of one of the perforating members, and Fig. 7 represents a portion of a strip of paper showing the characters perforated therein by the machine.

40 Similar characters designate like parts throughout the several figures of the drawings.

45 In the drawings, 10 is a weighted frame having secured to its rear end a cover 11.

The upper face of the frame 10 has secured thereto, by means of the screw 12, a plate 13 provided with a depression 14 in the forward end thereof, which depression is 60 adapted to contain an ink pad 15. Superimposed upon the plate 13 is a plate 16 having a plurality of alined perforations 17 there-in immediately over the inking pad 15. Above the under plate 16 and separated 65 therefrom except at its rear edge is a resilient plate 18 having a plurality of alined perforations 19 registering with the perforations 17. Riveted to the resilient plate 18 at 20 is a plate 21 provided with a plurality of forwardly extending fingers 22. The forward end of each of these fingers 22 is provided with a plurality of needles 23 disposed thereon and projecting from the under face thereof, these needles being positioned relatively to each other to form characters such as the numerals 1, 2, 3, etc., or letters forming the words "dollars" and "cents."

70 The upper face of each finger 22 is provided with a recessed pad 24. Between the plate 21 and the resilient plate 18 is a spring member 25 bearing against the end faces of the fingers 22 and normally retaining said fingers in raised position, as indicated in 75 Fig. 3 of the drawings. The rear edges of the plates 13, 16, and 18 bear against a shoulder 26 formed in the bed frame 10, and are all secured to said frame by means of the single screw 12. Beneath the plate 90 13 and riveted thereto and to the under plate 18 at 27 is a plate 28, the forward end of which has an inturned flange 29 forming a guide. The under face of the plate 13 has also secured thereto at 30 beneath the 95 recess 14 an angular member 31 provided with a guide groove 32. The forward end of the plate 13 is also provided with a guide groove 33 immediately above the groove 32. A plate 34 is adapted to travel longitudinally of the grooves 32 and 33, these grooves being parallel with the alined perforations 17 and 19. To the front face of this plate 100 34 is secured the member 35, said member having secured to its under side a projection 36 extending beneath the guide flange 29. The plate 34, member 35, and projecting member 36, form a carriage which is adapted to travel in a path parallel to and in front 105 of the alined perforations 17 and 19.

110 Pivoted at 37 to the plate 37^x secured to the upper portion of the member 35 is an

actuating member 38 having a recessed portion 39 adapted to receive the thumb or finger of the operator when it is desired to depress said actuating member 38. This actuating member 38 is normally retained in raised position by means of the spring 40 surrounding the pivot 37 with its ends extending rearwardly from said pivot and coacting respectively with the plates 37^x and 10 the inner wall of the actuating member 38. Secured to the rear end of the actuating member 38 is a block 41 projecting downwardly therefrom and having its lower end slightly curved. When the actuating member 38 is depressed the lower end of the block 41 will enter the recess in the pad 24 of a selected perforating member 22-23 and depress said member so that the needles thereof will pass through a check or other 20 piece of material inserted between the under plate 16 and the resilient plate 18. The downward movement of the actuating member 38 is limited by means of the upwardly extending projection 42 on said member 35. 25 When the needles 23 pass through the check or other material, the lower ends will extend into the ink pad 15 and cause the perforations to be inked on the return movement of the needles 23 to their normal position. The actuating member 38 has extending from one side thereof the studs 43-44. Between these studs 43-44 is positioned the rear end of a lever 45 pivoted at 46, the forward end of said lever having articulated thereto at 47 a downwardly extending member or pawl 48, the lower end of which is adapted to engage a ratchet 49 revoluble with a feed roll 50 mounted in the member 35. 30 40 When the actuating member 38 is depressed the stud 43 will strike the rear end of the lever 45 and move it about its pivot 46 so that the pawl member 48 will be raised a predetermined distance and engage new 45 teeth upon the ratchet 49. This pawl member 48 is of tempered steel and so constructed as to retain its engagement with the teeth of the ratchet 49 at all times. Secured to the member 35 is an ear 51 which 50 serves as a guide to insure the vertical movement of the pawl 48 when the lever 45 is moved about its pivot. When the actuating member 38 is returned to its normal position indicated in Fig. 3, the stud 44 will 55 engage with the lower edge of the lever 45 and depress the pawl 48, causing the ratchet 49 and feed roll 50 to be moved a predetermined distance about their axes. This movement of the feed roll moves the check 60 or other material a distance equal to the width of a perforating character and the space required between two successive characters. The feed roll 50 coacts with the bed roll 52 immediately above the feed roll 50 65 and mounted on a shaft 53 revoluble in ears

54 extending downwardly from the under portion of the U-shaped member 55 formed integral with the plate 37^x. The U-shaped member 55 is provided with extensions 56 adapted to be grasped by the fingers of the 70 operator and moved toward each other to lift the bed roll 52 from the feed roll 50 when it is desired to position the check or other material to be operated upon.

The member 35 has forwardly extending 75 brackets 57 each of which is provided with a plurality of slots 58. Supported on each of the brackets 57 is a plate 59 having an upwardly extending flange 60, said flanges serving as a guide for the forward edge of 80 the check or other material being operated upon. These plates 59 are provided with screws 61 extending through the slots 58 by which they may be clamped in adjusted position. When the members 59 and 60 have 85 been once adjusted for the size and style of check used in an office, no further adjustment thereof is required as long as that particular style of check remains in use.

The forward face of the plate 31 is provided with a plurality of detents 62, one for each of the perforating devices 22-23. In a recess in the rear face of the plate 34 is a spring member 63 provided with a V-shaped projection 64 adapted to enter one of the 95 detents 62 when the carriage has been moved along the guides 29, 32, and 33 into a position where the actuating member 38 registers with a selected perforating device 22-23.

The shaft 65 of the feed roll 50 extends 100 through the front wall of the member 35 and has secured thereto a ratchet 66. This shaft 65 also has loosely mounted thereon a manually controlled arm 67 carrying a spring finger 68 adapted to engage the 105 teeth of the ratchet 66 when said arm 67 has been moved about the axis of the shaft 65. The movement of the arm 67 in either direction is limited by the projecting studs 68^x and 69. This arm 67 is provided with an 110 index finger 70 movable over the surface of the cylindrical flange 71 projecting forwardly from the member 35. This flange is provided with designating character 72, which with the stud 68^x serves to indicate 115 the proper positions said arm 67 must be moved into to move the feed roll the required distance to remove the perforated portion of a check from beneath the "cents" and "dollars" perforating devices, so that 120 the perforation made by the next perforating member when depressed will not overlap the perforations formed by the "dollars" or "cents" perforating members. When the device is in operation the arm 67 is in 125 contact with the stop member 68^x and remains in this position whenever one of the narrow selected perforating members is operated.

It is self-evident from an inspection of 130

the drawings that the movable carriage is always centered with the center of the various perforating members, and these members vary in width, the "cents" perforating member being wider than the narrow perforating members carrying a single figure, while the "dollars" perforating member is much wider than the member used for perforating the word "cents". As a consequence of this variation in the width of the various perforating members, when it is desired to perforate the word "dollars" the arm 67 is moved to the right of Fig. 2 into contact with the stop member 69 and then is moved to the stud 68^x. This operation will move the paper a distance equal to the width of one-half of the width of the "dollars" perforating member, less one-half the width of one of the narrow perforating members. The "dollars" perforating member is then depressed and on the upward movement of the member 38 the paper will be fed a distance equal to the width of a narrow perforating member and the space between two perforated characters. After the "dollars" perforating member 74 has been depressed, the movement of the arm 67 to the stop 69 and back to the stop 68^x is repeated, and the device is in position for the operation of any one of the narrow perforating members 22, the last movement of the arm 67 having moved the paper a distance equal to one-half of the "dollars" perforating member less one-half the width of a narrow perforating member. When it is desired to perforate the word "cents" in the check, the arm 67 is moved into contact with the stop member 69 and then to the designating character 72, thereby moving the paper a distance equal to one-half the width of the "cents" perforating member less one-half the width of one of the narrow perforating members. The check perforating member is then in position for the "cents" perforating member 75 to be depressed. As the word "cents" is always the last word to be perforated and is to be followed by no other word or character, it is unnecessary to repeat the movement of the arm 67, as would be necessary if it was desired that any other character should follow said word "cents".

When the perforation of the check has been completed the perforations in the check 76 will look as shown in Fig. 7 of the drawings.

This provides a very simple construction of check protector containing a minimum number of parts and thereby making it inexpensive to construct.

It is believed that the operation and many advantages of this invention will be fully understood from the foregoing description.

Having thus described my invention, I claim:

1. In a device of the class described, the

combination of a plurality of aligned perforating devices; a carriage adapted to travel in a path parallel with said perforating devices; a member pivoted to said carriage and adapted to be moved about its pivot to 70 actuate a selected perforating device; a roll mounted on said carriage for feeding the material being operated upon; automatic means actuated by said pivoted member for moving said feed roll about its axis a predetermined amount; independent manually controlled means for moving said roll about its axis; and stop members for limiting the movement of said independent means in opposite directions. 80

2. In a device of the class described, the combination of a plurality of aligned perforating devices; a carriage adapted to travel in a path parallel with said perforating devices; a member pivoted to said carriage 85 and adapted to be moved about its pivot to actuate a selected perforating device; a roll mounted on said carriage for feeding the material being operated upon; automatic means actuated by said pivoted member for 90 moving said feed roll about its axis a predetermined amount; a ratchet wheel revoluble with said feed roll; an oscillating arm movable about the axis of said feed roll; and a resilient member secured to said arm and 95 normally engaging the teeth of said ratchet wheel.

3. In a device of the class described, the combination of a plurality of aligned perforating devices; a carriage adapted to 100 travel in a path parallel with said perforating devices; a member pivoted to said carriage and adapted to be moved about its pivot to actuate a selected perforating device; a roll mounted on said carriage for 105 feeding the material being operated upon; automatic means actuated by said pivoted member for moving said feed roll about its axis a predetermined amount; a ratchet wheel revoluble with said feed roll; an oscillating arm movable about the axis of said 110 feed roll; a resilient member secured to said arm and normally engaging the teeth of said ratchet wheel; and stop members on said carriage to limit the movement of said arm 115 in opposite directions.

4. In a device of the class described, the combination of a plurality of aligned perforating devices; a carriage adapted to 120 travel in a path parallel with said perforating devices; a member pivoted to said carriage and adapted to be moved about its pivot to actuate a selected perforating device; a roll mounted on said carriage for feeding the material being operated upon; 125 a ratchet wheel revoluble with said feed roll; a pawl engaging therewith; a spring for moving said pivoted member upward about its pivot; a pivoted lever articulated at one end to said pawl; and studs on said 130

pivoted member adapted to coact with the opposite end of said lever.

5. In a device of the class described, the combination of a plurality of alined perforating devices; a carriage adapted to travel in a path parallel with said perforating devices; a member pivoted to said carriage and adapted to be moved about its pivot to actuate a selected perforating device; a feed roll mounted on said carriage; 10 means for moving said roll about its axis predetermined amounts; a U-shaped resilient member above said feed roll having depending ears on its lowest arm, said resilient member forming a part of the carriage and moving therewith relatively to said perforating devices; and a bed roll revolvably mounted in said ears and normally contacting with said feed roll.

20 6. In a device of the class described, the combination of a frame; a plate secured thereto provided with alined depressions to receive inking pads; a plate superimposed thereon having alined perforations above 25 said inking pads; another resilient plate positioned above said perforated plate and provided with perforations registering with the perforations of the lower perforated plate; and a plurality of resilient members positioned above said resilient plate and each having a plurality of perforating needles normally above said resilient plate but adapted to be forced through the perforations in said resilient and under plates.

30 7. In a device of the class described, the combination of a frame; a plate secured thereto provided with alined depressions

35 to receive inking pads; a plate superimposed thereon having alined perforations above 40 said inking pads; another resilient plate positioned above said perforated plate and provided with perforations registering with the perforations of the lower perforated plate; and a plurality of resilient members 45 secured to said resilient plate, each having a plurality of perforating needles normally above said resilient plate but adapted to be forced through the perforations in said resilient and under plates.

50 8. In a device of the class described, the combination of a frame; a plate secured thereto provided with alined depressions to receive inking pads; a plate superimposed thereon having alined perforations above 55 said inking pads; another resilient plate positioned above said perforated plate and provided with perforations registering with the perforations of the lower perforated plate; a plurality of resilient members each 60 having a plurality of perforating needles normally above said resilient plate but adapted to be forced through the perforations in said resilient and under plates; 65 guide members secured to said under plate; a carriage movable on said guide members; and means mounted on said carriage for depressing a selected resilient needle-carrying member.

Signed by me at 4 Post Office Sq., Boston, 70 Mass., this 7th day of February, 1916.

SAMUEL T. THORSON.
